UNITED STATES PATENT OFFICE.

THOMAS FARMER, JR., OF NEW YORK, N. Y., ASSIGNOR TO RAILWAY IMPROVEMENT COMPANY, A CORPORATION OF NEW YORK.

HANGER-STRAP FOR CARS.

1,065,930.

Specification of Letters Patent.

Patented July 1, 1913.

Application filed February 21, 1912. Serial No. 679,047.

To all whom it may concern:

Be it known that I, THOMAS FARMER, Jr., a citizen of the United States, residing in the city, county, and State of New York, have made a certain new and useful Invention in Hanger-Straps for Cars, of which the following is a specification.

This invention relates to hanger straps for use on cars.

10 The object of the invention is to provide a construction of hanger straps which is simple, economical to manufacture and hygienic in use.

15 A further object of the invention is to provide a hanger strap for cars which is suitable to be readily cleaned when required.

20 The invention consists substantially in the construction, combination, location and relative arrangement of parts, all as will be more fully hereinafter set forth, as shown in the accompanying drawing, and finally pointed out in the appended claims.

25 Referring to the accompanying drawing,—Figure 1 is a view in elevation, parts being broken off and parts in vertical section, showing a construction of hanger strap embodying the principle of my invention. Fig. 2 is a view in transverse section on the line *a*, *a*, Fig. 1.

30 The ordinary leather hanger strap or hand hold ordinarily employed in cars for the use of standing passengers soon become soiled through contact with unclean hands by which they are grasped and often become charged with perspiration. In the dirty, greasy, discolored condition to which such straps are quickly reduced in use, they are not only offensive to the sight, but also serve as vehicles for the transmission of 35 disease germs including such as may be communicated to the delicate membranes of the eyes or other organs, by a hand which has been in contact with the infected strap.

40 It is among the special purposes of my present invention to provide a hand strap or hanger for use in cars which is not only sanitary and which avoids the objections of the possibility of accumulating disease germs by being grasped by dirty and per- 45 spiring hands, but also one which is capable of being readily cleansed when required, while at the same time being inexpensive to manufacture.

50 Referring to the accompanying drawing, reference letter *R* designates a rod such as

is usually employed in cars for the suspension of hand straps therefrom.

55 Reference letter *N* designates the strap. This may be made of leather or other suitable or convenient material and in the ordinary manner. This strap is formed into a small upper loop which embraces or encompasses the hanger rod *R* and into a larger pending or suspended loop which forms the hand grasp or hold to be grasped by standing passengers in the car.

60 In accordance with my invention I propose to employ a cover *P* for the suspending loop portion of the strap. This cover portion is in the form of a tube, though not necessarily a cylindrical tube and unsplit in cross section from end to end, and made of suitable non-absorbing material, preferably flexible and provided with a smooth polished exterior surface. This cover portion *P* is provided with a longitudinal bore therethrough and is made integral, that is, in one piece. It may be made of any suitable material and I have found a celluloid composition efficient for the purpose. Being 65 made of this material the hand strap is capable of being readily cleaned when desired. The loop portion of the hanger strap passes longitudinally through the bore of the cover.

70 A hanger strap constructed in accordance with my invention is exceedingly simple and economical to manufacture and affords a means for preventing the transmission of disease.

75 Having now set forth the object and nature of my invention and a construction embodying the principles thereof, what I claim as new and useful, and of my own invention, and desire to secure by Letters Patent 80 of the United States, is,—

85 1. A hanger strap or hand hold for cars comprising a suspended looped portion and a tubular cover portion therefor, of non-absorbent material, formed in one integral 90 piece unsplit in cross section from end to end and having a longitudinal bore, the loop portion of the strap passing longitudinally through the bore of the tubular portion.

95 2. A hanger strap or hand hold for cars comprising a suspended looped portion and a flexible tubular cover portion therefor, said flexible tubular cover portion being of non-absorbent material and formed in one integral piece unsplit in cross section from 100 105 110

end to end and having a central longitudinal bore, the loop portion of the strap passing longitudinally through the bore of the tubular portion, said tubular portion being longitudinally bent to conform to the shape of the loop portion.

In testimony whereof I have hereunto set

my hand in the presence of the subscribing witnesses, on this 13th day of Feby. A. D. 1912.

THOMAS FARMER, JR.
